UNITED STATES PATENT OFFICE.

JOHN B. FRANKE, OF FORT WAYNE, INDIANA, ASSIGNOR TO PERFECTION BISCUIT COMPANY, OF FORT WAYNE, INDIANA, A CORPORATION OF INDIANA.

CRACKER CASE.

Application filed January 26, 1924. Serial No. 688,874.

To all whom it may concern:

Be it known that I, JOHN B. FRANKE, a citizen of the United States, residing in Fort Wayne, in the county of Allen and 5 State of Indiana, have invented a new and useful Improvement in Cracker Cases, of which the following is a specification.

My invention has general reference to cracker cases of that type used by dealers 10 to display bulk quantities of crackers, or the like, to be sold out in small individual lots. Such cases generally have been known and used for many years and the invention, therefore, relates in particular to certain improvements and novel features as will hereinafter appear.

One of the important objects of the invention is the provision, in a cracker case of this character, of a heating device for 20 maintaining a suitable temperature and air condition to keep the crackers crisp and in best vendible condition.

Another object is the provision of such a heating device of convenient form and 25 mounting arrangement.

A further important purpose of the invention is to provide a display case of striking appearance, produced by means of an advertising sign thereon and means for illuminating said sign to attract the eye of a 30 customer.

It is also an object of the invention to provide the above features of advantage in conjunction with each other, since the heating device and light can be served from a 35 single electric wire and can be so related as to form a single convenient electric unit.

Numerous other objects and advantages of the invention will be apparent as it is better 40 understood from the following description, which, taken in connection with the accompanying drawings, discloses a preferred embodiment thereof.

Referring to the drawings,

Figure 1 is a front elevation of a cracker case in which my invention is embodied;

Fig. 2 is a front-to-back section thereof;

Fig. 3 is a detail section, taken substantially on the line 3-3 in Fig. 2;

Fig. 4 is a similar section, taken substantially on the section line 4-4 in Fig. 2;

Fig. 5 is a rear elevation of the case; and

Fig. 6 is a plan view of the heater mounting.

For the purpose of illustrating my inven-

tion, I have shown upon the drawings a cracker case in which it is embodied. Said case may be of any preferred general construction, being preferably of pleasing design and, in the present instance, being provided with glass panels on three sides thereof to expose the contents to view.

The case is formed with front corner uprights 21, side uprights 21' adjacent said front uprights and rear corner uprights 22, said uprights being connected at the top and bottom by cross pieces 23 and front-to-back pieces 24, forming a rectangular frame. A cover 25 is secured in place in any desired manner and facing strips 26 and 27 are 70 provided, respectively, at the top and bottom of the case to strengthen the same and give a pleasing appearance thereto. A cross board 28 at the bottom and a narrower board 29 at the top provide, with the front uprights 21, a casing for a glass pane 31. Side panes 32 are secured in upper and lower boards 33 and 34 and in the uprights 21' and 22. A thin rear board 35 is secured to cross pieces 36 and 37 and vertical strips 30 at- 80 tached to the inner side of the uprights 22.

Beneath the cross piece 37 there is provided a door 38 hinged at 39 to the bottom cross piece 23 and having an inwardly extending flange 40 adapted to fit within the strips 30 when said door is closed. A bottom member 41 is positioned upon the cross pieces 23 and 24 and extends rearwardly across the rear cross piece 23. Said door 38 is provided with a latch 42 and is adapted 90 to be turned down to horizontal position, as indicated in dotted lines in Fig. 2. The contents of the case may be removed by a scoop, or otherwise, through said door.

For the purpose of maintaining an even 95 temperature and a dry atmospheric condition within the case, I provide an electric heater, indicated generally at 43 and comprising a heating element secured by a plate 43' to the under side of a board 44 attached 100 to strips 45 adapted to be disposed diagonally across the lower part of the case. Cross pieces 46 connect the strips 45 at the center and top, a space being left at the bottom permitting the crackers to fall therethrough onto the floor 41. The mounting, as a whole, 105 is bodily removable from the case. The heater 43 is supplied with current by a wire 47 extending down inside the back board 35 and being secured to the edge of the mount- 110

ing board 44 by means of a collar 48. Said wire extends through the back board 35 to a switch 49 connected by wires 51 with any suitable source of current.

5 From the switch 49, a wire 52 leads forwardly to an electric light 53 mounted in a socket 54 depending from a supporting block 55, a reflector 56 being positioned upon said light. An advertising sign, indicated at 57 10 and, in the present instance, bearing the words "Hot P. W. crackers", is provided upon the front pane 31 and is adapted to be illuminated by the light 53. The body of the sign, as shown, is red with white letters thereon and the effect of the light behind the glass is to provide a striking appearance adapted to attract the attention of customers.

The crackers are kept in the best vendible 20 condition by means of the heater 43 and are displayed to advantage by means of the transparent walls of the case and illuminated sign just described. The light and heater may be served from the same source of current and the electrical attachments thus 25 form a single, easily positioned unit.

It is thought that the invention and many 30 of its attendant advantages will be understood from the foregoing description, and it will be apparent that various changes may be made in the form, construction and arrangement of the parts without departing from the spirit and scope of the invention, or sacrificing all of its material advantages, 35 the form hereinbefore described being merely a preferred embodiment thereof.

I claim:

1. A cracker case, comprising a display 40 holder having a door near the bottom thereof for removal of the crackers, a heater disposed within the holder adjacent said door, and a mounting for said heater extending diagonally across the lower part of the holder when positioned therein and having an 45 open section permitting the crackers to pass therethrough into position to be scooped up from said door.

2. A cracker case, comprising a display holder having a transparent wall therein, an advertising sign on a portion of said wall, 50 and means for illuminating said sign.

3. A cracker case, comprising a display holder having a transparent wall therein, an advertising sign on a portion of said wall, and an electric light disposed within the 55 holder behind said sign to illuminate the latter.

4. A cracker case, comprising a display holder having a transparent wall therein, a door near the bottom thereof for removal of 60 the crackers, a partially transparent advertising sign on a portion of said wall, illuminating means adjacent said sign, and deflecting means for confining the illumination of said illuminating means to the portion of 65 said transparent wall occupied by said advertising sign.

5. A cracker case, comprising, a display holder having a transparent wall therein, an electric heater disposed within said holder for conditioning crackers in said case, a partially transparent display sign, illuminating means adjacent said sign, and reflecting means for reflecting the light from 70 said illuminating means through said partially transparent display sign.

6. A cracker case, comprising, a display holder having a transparent wall therein, a door near the bottom of said holder for removal of the crackers, a partially transparent advertising sign on a portion of said wall, illuminating means adjacent said sign, deflecting means for confining illumination 75 of said illuminating means to the portion of said transparent wall occupied by said advertising sign, a heater disposed within the holder adjacent said door, and a mounting for said heater extending diagonally 80 across the lower part of the holder and having an open section permitting the crackers to be removed through said door.

JOHN B. FRANKE.
